UNITED STATES PATENT OFFICE.

ARTHUR K. LANDSMANN AND FRITZ DIPPON, OF ST. LOUIS, MISSOURI.

INTERNAL-COMBUSTION ENGINE.

1,122,773.

Specification of Letters Patent. Patented Dec. 29, 1914.

Application filed March 24, 1913. Serial No. 756,494.

To all whom it may concern:

Be it known that we, ARTHUR K. LANDSMANN and FRITZ DIPPON, subjects of the Emperor of Austria-Hungary, residing at St. Louis, in the State of Missouri, have invented certain new and useful Improvements in Internal-Combustion Engines, of which the following is a specification.

This invention relates to improvements in internal-combustion engines and the objects of the invention are to compress the explosive charge into a valve member which controls the intake and exhaust ports; the provision of a valve which in distinction to the "lift" or "puppet" valve, does not operate against the force of compression; the provision of a valve in which the necessity for periodical "grinding" and adjustment, found necessary with the "puppet" type valve, is eliminated; the provision of a valve which is noiseless in operation; the provision of a valve which, in distinction to the "puppet" valve, is not seated in the path of the intake and exhaust ports and, therefore, offers no obstruction to the rapid intake and exhaust of the explosive mixture; the provision of a valve which can be operated with extreme ease despite the highest degree of compression; and the provision of a valve in which loss of compression is rendered substantially impossible.

Other objects and advantages may be noted on consideration of the following portions of this specification and the appended claims.

Referring to the accompanying drawing, in which like numerals refer to like parts throughout the several views, Figure 1 a 40 sectional elevation depicting the cylinder of an engine equipped with our invention; Fig. 2 a top plan view of the devices shown in Fig. 1, a portion of the cylinder-head being removed; Figs. 3 and 4 detail views 45 of certain of the parts shown in Figs. 1 and 2 which shall hereinafter be more particularly described; and Fig. 5 a modification of certain of the features of the preferred form of our invention.

Numeral 1 indicates an engine cylinder provided with intake and exhaust ports 2, 2^a and inclosing a piston 3 connected with a crank-shaft 4 upon which is fixed a pinion 5 meshing with a gear 6, the latter adapted 55 to complete one revolution for every two revolutions of pinion 5. Gear 6 is keyed

upon a shaft 7 which carries an annular member 8 provided with a cam-groove 9 having an annular portion 9^a and in said groove is disposed a roller 10 secured to an arm of bell-crank lever 11 whose other arm is connected with a rod 12. Rods 12, 12^a, are slidably mounted in the wall of the cylinder and engage opposite sides of a laterally movable ring-valve 13 operating in a compartment 14 which communicates with piston chamber 15 by means of an aperture 16.

Valve 13 comprises a solid annular member 17, cast-iron split-rings 18 and vertically extensible sleeves 19 having beveled flanges 20. It will be noted that the edges of member 17 are beveled to afford a seat for the beveled edge of rings 18; that flanges 20 project over said rings; and that the latter are normally of smaller circumference than member 17, but are expanded, through the agency of their split feature, to substantially the same diameter as said member when flanges 20 are forced inwardly by the securing in place of cylinder head 21.

One of the important features of valve 13 lies in the provision of means for preventing loss of compression and this desideratum is attained by the use of split-rings 18, which as will be appreciated, gradually contract in response to the wearing away of flanges 20, whereby the latter are constantly retained in close engagement with the upper and lower walls of compartment 14.

An added valuable feature of valve 13 lies in the beveling of flanges 20, whereby should leakage of compression occur between said flanges and the walls of compartment 14 the danger of said flanges being forced away from said walls is reduced to the minimum in view of the small surface which would be subjected to the maximum pressure of the escaping gas.

The modification shown in Fig. 5 simply consists in squaring the edges of member 17 and seating therein a plurality of small springs 18^a in lieu of rings 18, said springs being compressed by flanges 20.

In operation, partial revolution of shaft 4 causes valve 13 to move into register with intake port 2 simultaneously with the descent of piston 3. The explosive mixture being thus drawn into chamber 15 is next compressed by the upward stroke of said piston into valve 13 which, during said stroke, remains stationary and out of reg-

ister with both the intake and exhaust ports due to the travel of roller 10 in the annular portion 9^a of groove 9. When piston 3 has reached the limit of its upward travel the charge is exploded by spark-plug 22 and the resulting expansion of the gas serves to depress said piston whose next upward stroke coincides with the registration of valve 13 with exhaust port 2^a.

10 The operation of the valve actuating mechanism may be more particularly described as follows. Referring to Fig. 1 it will be noted that valve 13 is out of register with both the intake and exhaust ports; 15 that piston 3 is on the compression stroke; and that during said stroke the said valve remains stationary due to the travel of roller 10 in the annular or non-actuating portion 9^a of the cam-groove 9, as described 20 in the preceding paragraph. At the completion of said compression stroke the charge is exploded through the agency of spark-plug 22 and piston 3 is driven downwardly. Coincident with the termination of said 25 downward movement of piston 3 roller 10 enters that portion of groove 9 designated by numeral 9^b which, as diagrammatically shown, is formed so as to lift said roller, thus actuating lever 11, forcing inwardly 30 rod 12 and placing valve 13 in communication with exhaust-port 2^a. Upon the substantial completion of the subsequent upward or gas-expelling stroke of piston 3 valve 13 is instantly cut off from port 2^a 35 and simultaneously placed in communication with intake port 2 by the entrance of roller 10 into that portion 9^c of groove 9 which, as shown, is inwardly curved (at its commencement) toward the axis of member 8 40 and thus serves to depress said roller which results in moving outwardly arm 11 and rod 12. The neutral position of valve 13 shown in Figs. 1 and 4 is assumed when roller 10 is slightly lifted on entering the 45 before-described portion 9^a of groove 9 and it will be appreciated that but very slight movement of said valve is required to open one of said ports and close the other.

What we claim as new and desire to secure by patent is:—

1. An internal combustion engine comprising a cylinder, intake and exhaust ports therein, a piston, a member controlling the communication of said ports with said cylinder; and means for automatically moving said member into and out of register with said ports, said member comprising oppositely extensible sleeves, and devices for automatically extending said sleeves in compensation for the wear thereof.

2. An internal-combustion engine comprising a cylinder, intake and exhaust ports therein, a piston, a member controlling the communication of said ports with said cylinder; and means for automatically moving

said member into and out of register with said ports, said means adapted to maintain said member out of register with said ports during compression of said charge, said member comprising oppositely extensible sleeves, and devices for automatically extending said sleeves in compensation for the wear thereof.

3. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, said member comprising oppositely extensible sleeves adapted to engage opposite walls of said compartment, and devices for automatically extending said sleeves in compensation for the wear thereof.

4. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, said means adapted to maintain said member out of register with said ports during compression of said charge, said member comprising oppositely extensible sleeves adapted to engage opposite walls of said compartment, and devices for automatically extending said sleeves in compensation for the wear thereof.

5. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, said member comprising extensible sleeves having beveled flanges adapted to engage opposite walls of said compartment, and devices for automatically extending said sleeves in compensation for the wear of said flanges.

6. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, said means adapted to maintain said member out of register with said ports during compression of said charge, said member comprising extensible sleeves having beveled flanges adapted to engage opposite walls of said compartment, and devices for auto-

10 matically extending said sleeves in compensation for the wear of said flanges.

7. An internal-combustion engine comprising a cylinder, intake and exhaust-ports therein, a piston, a member controlling said ports adapted to reciprocate in a plane transverse to the axis of said cylinder, and means for automatically moving said member into and out of register with said ports, 10 said member comprising oppositely extensible sleeves, and devices for automatically extending said sleeves in compensation for the wear thereof.

8. An internal-combustion engine comprising a cylinder, intake and exhaust-ports therein, a piston, a member controlling said ports adapted to reciprocate in a plane transverse to the axis of said cylinder, and means for automatically moving said member into and out of register with said ports, 15 said means adapted to maintain said member out of register with said ports during compression of said charge, said member comprising oppositely extensible sleeves, 20 and devices for automatically extending said sleeves in compensation for the wear thereof.

9. An internal-combustion engine comprising a cylinder, intake and exhaust-ports 25 therein, a piston, a compartment between said ports and piston, a member disposed in said compartment adapted to reciprocate in a plane transverse to the axis of said cylinder, and means for automatically moving said member into and out of register with 30 said ports, said member comprising oppositely extensible sleeves adapted to engage opposite walls of said compartment, and devices for automatically extending said sleeves in compensation for the wear thereof.

10. An internal-combustion engine comprising a cylinder, intake and exhaust-ports therein, a piston, a compartment between said ports and piston, a member disposed in said compartment adapted to reciprocate in a plane transverse to the axis of said cylinder, and means for automatically moving said member into and out of register with 35 said ports, said means adapted to maintain said member out of register with said ports during compression of said charge, said member comprising oppositely extensible sleeves adapted to engage opposite walls of said compartment, and devices for automatically extending said sleeves in compensation for the wear thereof.

11. An internal-combustion engine comprising a cylinder, intake and exhaust-ports 40 therein, a piston, a compartment between said ports and piston, a member disposed in said compartment adapted to reciprocate in a plane transverse to the axis of said cylinder, and means for automatically moving said member into and out of register with

45 said ports, said member comprising extensible sleeves having beveled flanges adapted to engage opposite walls of said compartment, and devices for automatically extending said sleeves in compensation for the 70 wear of said flanges.

12. An internal-combustion engine comprising a cylinder, intake and exhaust-ports therein, a piston, a compartment between said ports and piston, a member disposed in said compartment adapted to reciprocate in a plane transverse to the axis of said cylinder, and means for automatically moving said member into and out of register with 75 said ports, said means adapted to maintain said member out of register with said ports during compression of said charge, said member comprising extensible sleeves having beveled flanges adapted to engage opposite walls of said compartment, and devices for automatically extending said sleeves in compensation for the wear of said flanges.

13. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, 80 said member being closed above and substantially closed below by opposite walls of said compartment.

14. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, 85 said means adapted to maintain said member out of register with said ports during compression of said charge, said member being closed above and substantially closed below by opposite walls of said compartment.

15. An internal-combustion engine comprising a cylinder, intake and exhaust ports therein, a piston, a compartment between said ports and piston, a member disposed in said compartment adapted to contain the charge compressed by said piston, and means for automatically moving said member into and out of register with said ports, 90 said member being closed above and substantially closed below by opposite walls of said compartment and comprising extensible sleeves adapted to engage said walls, and devices for automatically extending said sleeves in compensation for the wear thereof.

16. An internal-combustion engine comprising a cylinder, intake and exhaust ports therein, a piston, a compartment between 130

- 60
said ports and piston, a member disposed in
said compartment adapted to contain the
charge compressed by said piston, and means
for automatically moving said member into
5 and out of register with said ports, said
means adapted to maintain said member
out of register with said ports during com-
pression of said charge, said member being
closed above and substantially closed be-
10 low by opposite walls of said compartment
and comprising extensible sleeves adapted
to engage said walls, and devices for auto-
matically extending said sleeves in com-
pensation for the wear thereof.
15 17. An internal-combustion engine com-
prising a cylinder, intake and exhaust ports
therein, a piston, a compartment between
said ports and piston, a member disposed in
said compartment adapted to contain the
20 charge compressed by said piston, and means
for automatically moving said member into
and out of register with said ports, said
member being closed above and substan-
tially closed below by opposite walls of said
25 compartment and comprising extensible
sleeves having beveled flanges adapted to
engage said walls, and devices for automatic-
ally extending said sleeves in compensation
for the wear of said flanges.
30 18. An internal-combustion engine com-
prising a cylinder, intake and exhaust ports
therein, a piston, a compartment between
said ports and piston, a mem-
35 ber disposed in said compartment adapt-
ed to contain the charge compressed by
said piston, and means for automatically
moving said member into and out of register
with said ports, said means adapted to
40 maintain said member out of register with
said ports during compression of said
charge, said member being closed above and
substantially closed below by opposite walls
of said compartment and comprising ex-
45 tendsible sleeves having beveled flanges
adapted to engage said walls, and devices
for automatically extending said sleeves in
compensation for the wear of said flanges.
19. An internal-combustion engine com-
50 prising a cylinder, intake and exhaust ports
therein, a piston, a compartment between
said ports and piston, a member disposed in
said compartment adapted to reciprocate in
a plane transverse to the axis of said cyl-
55 inder, and means for automatically moving
said member into and out of register with
said ports, said member being closed above
and substantially closed below by opposite
walls of said compartment and comprising
extensible sleeves adapted to engage said
walls, and devices for automatically extend-
ing said sleeves in compensation for the
wear thereof.

- walls, and devices for automatically extend-
ing said sleeves in compensation for the
wear thereof.
20. An internal-combustion engine com-
prising a cylinder, intake and exhaust ports
therein, a piston, a compartment between
said ports and piston, a member disposed in
said compartment adapted to reciprocate in
a plane transverse to the axis of said cyl-
inder, and means for automatically moving
said member into and out of register with
said ports, said means adapted to maintain
said member out of register with said ports
during compression of said charge, said
member being closed above and substantially
closed below by opposite walls of said com-
partment and comprising extensible sleeves
adapted to engage said walls, and devices
for automatically extending said sleeves in
compensation for the wear thereof.
21. An internal-combustion engine com-
prising a cylinder, intake and exhaust ports
therein, a piston, a compartment between
said ports and piston, a member disposed in
said compartment adapted to reciprocate in
a plane transverse to the axis of said cyl-
inder, and means for automatically moving
said member into and out of register with
said ports, said member being closed above
and substantially closed below by opposite
walls of said compartment and comprising
extensible sleeves having beveled flanges
adapted to engage said walls, and devices
for automatically extending said sleeves in
compensation for the wear of said flanges.
22. An internal-combustion engine com-
prising a cylinder, intake and exhaust ports
therein, a piston, a compartment between
said ports and piston, a member disposed in
said compartment adapted to reciprocate
in a plane transverse to the axis of said cyl-
inder, and means for automatically moving
said member into and out of register with
said ports, said means adapted to maintain
said member out of register with said ports
during compression of said charge, said
member being closed above and substantially
closed below by opposite walls of said com-
partment and comprising extensible sleeves
having beveled flanges adapted to engage
said walls, and devices for automatic-
ally extending said sleeves in com-
pensation for the wear of said flanges.
